UNITED STATES PATENT OFFICE

131,295

DESIGN FOR AN AIRPLANE

Edward F. Burton and William Bailey Oswald,
West Los Angeles, Calif., assignors to Douglas
Aircraft Company, Inc., Santa Monica, Calif.

Application April 28, 1941, Serial No. 100,669

Term of patent 7 years

To all whom it may concern:

Be it known that we, Edward F. Burton and William Bailey Oswald, both citizens of the United States and both residents of West Los Angeles, in the county of Los Angeles and State of California, have invented a new, original, and ornamental Design for an Airplane, of which the following is a specification, reference being had to the accompanying drawings, forming part thereof.

Figure 1 is a plan view of the subject airplane showing my new design;

Figure 2 is a front elevational view of the airplane depicted by Figure 1;

Figure 3 is a side elevational view of the airplane depicted by Figure 2;

Figure 4 is a top perspective view of the airplane in flight; and

Figure 5 is a bottom perspective view of the airplane in flight.

We claim:

The ornamental design for an airplane, substantially as shown.

EDWARD F. BURTON.
WILLIAM BAILEY OSWALD.
